SAFETY WINDOW LOCK

Harry E. Bundren and Victor A. Vicksell,
Kansas City, Mo.

Application May 12, 1947, Serial No. 747,404

6 Claims. (Cl. 292—254)

1

This invention has to do with the field of building and construction and particularly with windows, the primary object being to provide a lock for windows operable to automatically maintain the window in the locked condition until the operator thereof actuates certain elements to unlock the same.

It is well known by those skilled in the art that heretofore many types of locking devices have been provided for windows but for the most part, all of such locks require actuation of certain elements to move the same into the locked position. Such construction of the conventional types of window locks leads to the common defect of being inoperative except when the operator actually remembers to lock the window when the same has been moved to the closed position.

Another defect of the common type of locking means for windows is that of providing no means for preventing further opening of the window when the same is left in the partially opened condition.

The most important object of this invention is to provide a window lock which obviates all of the aforesaid defects through the medium of a resilient member normally disposed in the path of travel of the window to limit the extent of opening thereof except when such member is actually moved out of its operating position.

Another important object of this invention is to provide a window lock having the aforesaid resilient member disposed in the path of travel of the window and having a swingable cam member mounted upon the window for movement to and from a position where the same contacts and moves the resilient member into the operative position when so desired by the operator.

Other objects of this invention include the way in which a plate is attached to the window and having a swingable cam element affixed thereto for actuating the resilient member; the way in which such cam member is automatically moved to the inoperative position when the window is moved toward the closed position; the way in which the swingable cam member is formed to prevent accidental movement thereof to the operative position as the window is closed; and the way in which the entire lock is made from a minimum of parts to render the same inexpensive, simple and easy to construct and to operate.

Minor objects of this invention will be made clear or become apparent during the course of the following specification, reference being had to the accompanying drawing, wherein:

2

Fig. 1 is a side elevational view of a window showing the safety window lock made in accordance with the present invention attached thereto.

Fig. 2 is an enlarged, detailed, fragmentary cross-sectional view taken on line II—II of Fig. 1.

Fig. 3 is a cross-sectional view taken on line III—III of Fig. 2 and looking in the direction of the arrows.

Fig. 4 is a fragmentary, detailed, side elevational view similar to that shown in Fig. 1 but on an enlarged scale.

Fig. 5 is a perspective view of the plate member and cam element per se; and

Fig. 6 is an inverted plan view of the elements shown in Fig. 5.

The safety window lock about to be described is particularly adapted for use with double-hung windows 10 and 12 of the kind illustrated in Fig.

20 1. The lock per se comprises three main parts, namely, a plate member 14, a cam element 16 and a resilient finger or arm 18. The finger 18 comprises a relatively narrow elongated leaf spring fastened at one end thereof to the window 10 through the medium of a pair of screws or the like 20. This finger 18 depends downwardly and outwardly from its point of connection with the window 10, as illustrated in Fig. 2 and has the lowermost end thereof normally disposed in the path of travel of the window 12.

Any number of fingers 18 may be mounted upon the window 10 as desired, to the end that window 12 or window 10 may be moved to any desired open position. In other words, the uppermost of these fingers 18 should be disposed at a position where the same will prevent opening of window 12 or window 10 more than a relatively small distance. This distance should be such as to prevent an intruder from passing his hand inwardly and to a position where he might actuate member 18 to prevent further opening of either the windows 10 or 12.

45 The plate member 14 is provided with a pair of openings 22 and 24 for receiving a like number of screws or the like 26 and 28 respectively, serving as a means of fastening this plate member 14 to the uppermost end of the window 12. This plate member 14 and the cam element 16 attached thereto, is disposed in direct underlying relationship with the respective resilient arms 18 and a flange 30 overlaps a portion of the window 12 to cooperate with the screws 26 and 28 in maintaining rigidity in the plate member 14.

50 Plate 14 is provided with a pair of opposed slits 32 and 34 for presenting a pair of flaps 36 and

38 respectively. These flaps 36 and 38 are bent upwardly to present a pair of barrels 40 and 42 for receiving a shaft 44 of the cam member 16. This shaft 44 is integral with the cam element 16 and formed by cutting a pair of notches 46 and 48 near one end thereof. A pair of notches 50 and 52 are also formed in the cam element 16 and the plate 14 respectively to prevent swinging of cam element 16 with respect to plate 14 when such is desired. Thus, cam element 16 is substantially H-shaped, the two opposed shaft portions 44 forming one leg thereof and a lip 54 being formed on the other leg as hereinafter explained.

The notch 50 is a continuation of the notch 46 of cam element 16 and the notch 52 is formed in the barrel 40 of the plate 14. When these notches 50 and 52 are in the interlocking position shown in Fig. 5 which is made possible by sliding the shaft 44 transversely with respect to plate 14, 15 the swinging movement of cam element 16 is prevented.

The element 16 is provided with the curved laterally extending lip 54 which extends upwardly from the window 12 when element 16 is in the operative position and is disposed downwardly when in the operative position as illustrated by dotted lines in Fig. 2.

A hole 56 formed in the element 16 receives the head of screw 26 when cam element 16 is in the operative position shown in Fig. 2 to prevent shifting of the element 16 due to a loose fit between the shaft 44 and the barrels 40 and 42 when the lip 54 comes into contact with the respective resilient arms 18 as about to be described.

In operation, it is clear that when the element 16 is swung upon the plate 14 to the position illustrated in dotted lines in Fig. 2, the extent of upward movement of window 12 and the extent of downward movement of window 10 is limited by the lowermost resilient arm 18 contacting the uppermost face of the plate 14 on window 12. When it is desired to raise or lower the windows 12 and 10 respectively, the operator moves the cam member 16 to the full line position illustrated in Fig. 2. As window 12 is raised or the window 10 lowered, the curved lip 54 comes into contact with the lowermost end of the arms 18 and depresses the latter against the window 10, permitting further relative movement of the windows 10 and 12. This same action takes place between the lip 54 and the next arm 18 as the window 12 is caused to be moved upwardly beyond the lowermost flexed arm 18. Upon closing of the windows, the arms 18 will move to the normal position illustrated in Fig. 2 automatically because of their resilient character as soon as the window 12 moves out of contact therewith. As this closing movement takes place, and as the arms 18 move outwardly to the normal position, the latter come into contact with the lip 54 of cam 16 and automatically flip the same to the dotted line position illustrated in Fig. 2. Thus, as window 12 and window 10 are moved to the closed position, the same become automatically locked because the cam element 16 has been moved by the arms 18 to the inoperative position. The element 16 will not accidentally return to the operative position because of the polygonal cross-sectional contour of the shaft 44 as illustrated in Fig. 5. In the event the operator desires to further prevent any possibility of the element 16 being accidentally moved to the operative position, he may shift the element 16 to a position where the notches 50 and 52 are interlocked. Obviously, any num-

ber of the fingers 18 may be mounted upon the window 10 and the disposition thereof is optional.

In the drawing, and particularly Fig. 1, there has been shown a pair of locks, one mounted upon each side of the window 12 and each having corresponding fingers 18. Obviously, only one of these locks is necessary and may be mounted on either side of the windows 10 and 12. By the same token, if used with windows where the uppermost sash 10 is immovable, the arms 18 may be disposed upon the framework of the windows and the plate 14 turned accordingly if desired.

The advantages emanating from use of the self-locking device for windows just described, are numerous and although but one form thereof has been illustrated and described, it is understood that many changes may be made in details of construction without departing from the spirit of this invention or scope of the appended claims.

Having thus described the invention, what is claimed as new and desired to be secured by Letters Patent is:

1. A lock for rectilinearly reciprocable windows comprising a plate member adapted for attachment to a window to be locked; a cam element swingably secured to said plate member; and shiftable means disposed in the path of travel of said window and positioned to limit the extent of movement of the window in one direction; said cam element being movable to and from a position rendering said shiftable means inoperable as the window is moved in said one direction, said shiftable means comprising a resilient stop, said cam element being operable to depress the stop 35 out of the path of travel of said window.

2. A window lock of the character described, comprising a plate mounted upon one end of the window to be locked; an element having an upturned lip on one end thereof, said element being hingedly secured at its opposite end to said plate; and shiftable means normally disposed in the path of travel of the window for limiting the extent of movement thereof in one direction, said lip of the element being engageable with the shiftable means for rendering the latter inoperable as the window is moved in said one direction and when the element is swung on the plate to a predetermined position relative thereto.

3. A window lock of the character described, comprising a plate mounted upon one end of the window to be locked; an element having an upturned lip on one end thereof, said element being hingedly secured at its opposite end to said plate; and shiftable means normally disposed in the path of travel of the window for limiting the extent of movement thereof in one direction, said lip of the element being engageable with the shiftable means for rendering the latter inoperable as the window is moved in said one direction and when the element is swung on the plate to a predetermined position relative thereto; said shiftable means comprising a resilient stop capable of returning to an operable position when the window is shifted in the opposite direction.

4. A window lock of the character described, comprising a plate mounted upon one end of the window to be locked; an element having an upturned lip on one end thereof, said element being hingedly secured at its opposite end to said plate; and shiftable means normally disposed in the path of travel of the window for limiting the extent of movement thereof in one direction, said lip of the element being engageable with the shiftable means for rendering the latter inoperable as the window is moved in said one direction and

when the element is swung on the plate to a predetermined position relative thereto, said shiftable means comprising a resilient stop capable of returning to an operable position when the window is shifted in the opposite direction, said element being freely swingable on the plate whereby the same is shifted to another position on the plate by the resilient stop as the latter returns to its operable position.

5. A window lock of the character described, comprising a resilient member mounted with one end thereof normally in the path of travel of the window to be locked to limit the extent of movement of the window in one direction; and a cam element having means for swingably attaching the same to said window, said cam element engaging the resilient member and depressing the same out of the path of travel of the window when the cam element is swung to a predetermined position on the window, said resilient member returning to said normal position as the window is moved toward its starting position in the opposite direction, said member swinging the cam element out of said predetermined position as the member returns to the normal position.

6. A window lock of the character described, comprising a resilient member mounted with one end thereof normally in the path of travel of the

window to be locked to limit the extent of movement of the window in one direction; a cam element having means for swingably attaching the same to said window, said cam element engaging the resilient member and depressing the same out of the path of travel of the window when the cam element is swung to a predetermined position on the window, said resilient member returning to said normal position as the window is moved toward its starting position in the opposite direction, said member swinging the cam element out of said predetermined position as the member returns to the normal position; and releasable means for holding the cam element in an inoperative position on the window.
